STEAM OR ELASTIC FLUID GENERATOR,
WITH POSITIVE PRESSURE FURNACEGeorge W. Kessler, New York, N. Y., assignor to
The Babcock & Wilcox Company, Rockleigh,
N. J., a corporation of New Jersey

Application February 1, 1949, Serial No. 73,974

11 Claims. (Cl. 122—235)

1

This invention relates to fluid heat exchange apparatus, and it is herein exemplified in vapor or steam generators.

The invention is concerned with a water tube type of steam or vapor generator in which there is incorporated a furnace particularly adapted for operation at high positive pressures.

The invention involves the provision of a steam or vapor generator characterized by the arrangement of its furnace and pressure parts within a casing which is of pressure constraining shape in plan. More particularly, the invention involves a steam or vapor generating unit in which the pressure parts including a superheater are arranged, with the furnace, within a circular casing adapted for effective operation at high furnace gas pressures.

Another object of the invention is to provide, in a steam or vapor generating installation of the type indicated, a plurality of furnaces one of which is operated in accordance with vapor generating requirements, and the other independently fired for maintaining an optimum superheat.

In general, the invention involves a central pressure vessel construction involving, in a unitary structure, the lower water chamber, a superposed downcomer, and an upper vapor and liquid chamber acting as a central support for the installation and having banks of fluid heating tubes and the furnace disposed in an annular arrangement around the central pressure vessel construction and within a pressure tight casing connected to the upper and lower chambers.

The objects of the invention are obtained in a structure which is illustrated in preferred forms in the accompanying drawings wherein:

Fig. 1 is a dual plane vertical section of the installation taken on the section lines 1—1 of Fig. 3;

Fig. 2 is a vertical section through the installation on the section line 2—2 of Fig. 3;

Fig. 3 is a horizontal section on the plane of the section line 3—3 of Fig. 1;

Fig. 4 is a concentric or arcuate section through the separator on the line 4—4 of Fig. 1;

Fig. 5 is a detailed view showing the manner in which the exterior casing is associated with the upper part of the central pressure vessel construction;

Fig. 6 is a horizontal section illustrating a modified type of vapor generator in which there is a separately fired superheater, operated to obtain the desired steam temperature;

Fig. 7 is a horizontal section of a further modi-

fication in which a separate superheater gas pass is provided with its own separate gas flow controlling means for superheat regulation;

Fig. 8 is a horizontal section of a further modification in which a separate superheater gas pass is disposed in one of two arcuate gas passes leading from a single furnace to separate gas flues, and

Fig. 9 is a horizontal section of another modification in which the furnace gases are divided between a superheater gas pass and a steam generating gas pass, the separate passes leading to a single flue with gas flow regulating means therein.

15 The drawings illustrate a vertically extending steam or vapor generator of cylindrical form, including an upper cylindrical steam and water drum 10, and a lower water chamber 12, the drum and the chamber having heads 10' and 12' which are substantially semi-elliptical in cross section. The chamber 12 may also be appropriately referred to as a submerged cylindrical drum because of its shape and because of the fact that it is normally submerged, in the sense 20 in which that expression has been used in the steam generator art. It may also be referred to as a water drum. These chambers, or drums, are integrally connected by central downcomer 14 of relatively large diameter to form a unitary 25 pressure vessel construction.

The above construction is centrally located and it is co-axial with an upright cylindrical outer wall or casing generally indicated at 16 and including substantially semi-elliptical, or dished heads 16' and 16'', and arranged within this wall construction are the steam generating and steam superheating tubes. These tubes are clearly shown as arranged within an annulus between the downcomers 14 and the wall 16. The 30 bank of steam generating tubes is generally indicated at 18 in Figs. 2 and 3 and the superheater is generally indicated at 20. The steam generating tubes are arranged in radial rows as indicated in Fig. 3, most of these rows extending from the central downcomer 14 to the outer wall 16. These tubes are arranged so as to have their inlets connected to the water chamber 12 and their outlets connected to the steam and water drum 10 in the manner indicated in Fig. 2.

40 Part of the furnace gases for heating the steam generating tubes originate in a furnace 22, fired by means such as the burner 24. The gases from this furnace pass in the direction of the arrows 25—27 to the flue 30, thereby passing 45 between and over the steam generating tubes.

The steam generating tubes are also heated by gases from the furnace 60, after they have passed over the superheater 20.

Gases from the furnace 22 first contact a bank 32 (Fig. 3) of relatively large diameter steam generating tubes connected to the upper and lower chambers 12 and 10 in a manner similar to that in which the tubes 33 are so connected. This bank of steam generating tubes acts as a radiant heat screen for the main bank of steam generating tubes 18 which are of smaller diameter.

A wall for the furnace 22, at the left hand side of the burner 24 (Fig. 3) is formed by the radially spaced wall tubes 34 arranged in a radial row and being provided with a stud tube and refractory construction 36 closing the spaces only in a vertical position adjacent the burner 24. Gases from the superheater 20 can readily pass to furnace 22 above, and beneath this stud tube construction. This construction is generally similar to the stud tube wall shown in Fig. 3 of the Bailey et al. Patent 1,999,934, April 30, 1935.

The outer wall of the furnace 22 and the associated gas pass for the steam generating tubes 18 is delineated by upright wall tubes such as 40-44, these tubes being connected at their lower ends to the water chamber 12 and at their upper ends to the steam and water chamber 10, the spaces between these tubes being closed by a stud tube construction similar to that associated with the tubes 34.

The burner opening 50 for the furnace 22 is formed by an annular body of refractory 52 supported and thermally maintained by wall tubes similar to the tubes 40-44 and other wall tubes 54-57 which are bent out of their wall formation in the zone of the burner opening 50 to conform to and protect the burner opening.

A similarly constructed furnace for operation in accordance with the superheat requirements is indicated at 60. This furnace is fired by a burner 62. The gases generated in the furnace 60 pass generally in the direction of the arrows 64-67, and above and beneath the stud tube construction 36, into the furnace 22, and thence through the bank of steam generating tubes 18, to the flue 30.

The boundaries of the furnace 60 and its associated superheater gas pass are formed by outer wall tubes such as 70-74 constructed and arranged in a manner similar to that of the outer wall tubes 40-44, and a radially extending wall generally indicated at 80 and having stud tube constructions similar to those of the radial wall for the furnace 22, involving tubes 34. An additional boundary for the furnace 60 involves the stud tube wall construction 90 extending radially from the downcomer 14 to an arcuate wall 92 which is similarly formed by a stud tube wall construction involving upright tubes connected into the circulation by communication with the chambers 10 and 12 of the central pressure vessel construction.

Between the furnace 60 and the superheater gas pass, and between the outer casing and the inner arcuate wall 92 is a radiant heat screen 94 including three radially arranged rows of large diameter steam generating tubes disposed on relatively wide centers. The different rows of these tubes are indicated at 96-98. These rows, like the radial rows of steam generating tubes 18 and the radial row of tubes comprising the wall 80, extend inwardly to a position closely adjacent steam generating tubes such as 100-105 disposed

in circular arrangement and in contiguous relation about the downcomer 14 to thereby protect the latter from overheating. The manner in which similar tubes are formed and connected to the upper and lower water chambers is indicated in Figs. 1 and 2 at 110-113. Arcuate rows of contiguous tubes such as tubes 111 and 111' (Fig. 1) have their upper portions such as 112 disposed along the surface of the upper drum and their lower portions such as 113 similarly disposed on the surface of the lower drum 12. Tubes of the two contiguous rows (such as 111 and 111'-Fig. 1) may have their upper ends in one circumferential row where they are connected to the large diameter portion of the upper drum, and may have their lower ends similarly connected to the lower drum 12.

The two rows of downcomer protecting tubes such as 111, 111', 115 and 116 are arranged directly opposite the burner 24, and similarly arranged rows of tubes such as 117-119, 104, and 105 are disposed opposite burner 62 (Fig. 3).

The steam generating tubes communicate at their upper ends with an annular inlet chamber 120 (Fig. 1) between the wall of the steam and water chamber 10 and a central cylindrical construction 122. The latter has a contracted lower portion 124 communicating with a vortex inhibitor 126, thus providing for the flow of separated water from the cylindrical whirl chamber 130 downwardly through the annular opening 132, in the direction of the arrow 134. The portion 124 forms a separated liquid outlet communicating with the downcomer 14 and the lower drum or chamber 12.

The steam and water mixture from the steam generating tubes passes upwardly in the annular chamber 120 in the direction indicated by the arrows 136-138, and through tangential inlet constructions 140 to the top of the whirl chamber 130. These constructions constitute, with their associated parts, means whereby vapor and liquid mixtures from the vapor generating tubes are caused to be discharged tangentially into the separator, or the whirl chamber 30. The steam separated within the whirl chamber 130 passes upwardly through an auxiliary separator 142 to the steam space of the chamber 10, whence it passes downwardly through upright tubes such as 144, 146 to extensions 150 and 152 of a superheater inlet header 154.

From the inlet header 154 the steam passes through banks of superheater tubes 160-163 formed by reversely bent tubes in the manner indicated in Fig. 4. From these tubes, the steam passes to an outlet header 166, and thence through a tubular connection 168 to a point of further treatment or use.

The specific construction of the steam and water separator of which the whirl chamber 130 is a part, is shown and claimed in the co-pending application of Ammon, Serial No. 73,985 dated February 1, 1949.

The cylindrical wall construction for the entire installation, in addition to the wall tubes such as 40-44 and 70-74, involves a casing including a generally cylindrical metallic shell, or upright casing, 180 between which and the upright wall tubes there is a stratum 182 of thermal insulation. Externally of the metallic shell 182 is outer stratum 184 of thermal insulation disposed between spaced metallic supports such as 190-195 (Fig. 1) secured to the shell 180.

The casing has an access opening 68 and the metallic shell 180 is provided with an aligned

opening normally closed by a closure member welded therein as indicated in the upper left hand part of Fig. 1.

Fig. 1 of the drawings clearly shows the vertically intermediate portion of the water drum 12 to have a cylindrical section, the walls of which are considerably thicker than the head of that drum. This drawing also shows a water drum as having walls which are considerably thicker than the walls of the downcomer 14. Similarly, Fig. 1 of the drawing clearly shows the vertical intermediate part of the upper drum 10 to have cylindrical section adjacent the lower part of the whirl chamber 30 of a wall thickness greater than the wall thickness of the head of that drum, and considerably greater than the thickness of the wall of the downcomer 14. The reason for these constructions involving intermediate drum sections of greater wall thickness is to provide adequate drum ligament strength, considering the greater number of steam generating tubes which are expanded into tube holes in the vertically intermediate sections of the drums.

Water is supplied to the chamber 12 through a tubular feed water inlet connection 200 including tubular element 202 passing through the lower wall of the pressure vessel element forming the chamber 12, and the installation is held in place by a circular support secured at the base of the central pressure vessel construction and including the elements 204 and 206. Other supporting elements radially arranged about the shell 180 and fixedly secured thereto are indicated at 208 and 210 (Fig. 1).

The lower end of shell 180 is fixed to the lower pressure vessel 12 at 179, and the upper end of the shell is secured to the wall of the pressure vessel part forming the upper chamber 10 in the manner indicated in Fig. 5. Here, the shell 180 is welded at 220 to a collar 222 which is held in operative pressure tight relation to the wall of the steam and water chamber 10 by the metallic ring 224, associated securing devices 226-228, and a gasket device 230. The purpose of this construction and a similar construction at the bottom of the casing is to provide gas-tight connections between the centrally disposed pressure vessel and the shell 180, to enable the installation to effectively operate at positive furnace gas pressures which are relatively high.

The modifications illustrated in Figs. 6 to 9, inclusive, are similar to the embodiment above described in that each includes a central drum and downcomer assembly like that shown in Figs. 1 and 2, the circumscribing casing being disposed about the assembly and joined to the upper and lower drums in a pressure tight manner. Each also includes a bank of steam generating tubes and a bank of superheater tubes disposed within the annular space between the casing and the central assembly of downcomer and drums.

The Fig. 6 modification involves two furnaces 250 and 252 separated by a radial wall 254 which includes steam generating tubes such as 256-258 with intervening stud and refractory constructions such as 260. The wall extends from the casing wall tubes such as 262 to a position adjacent the downcomer 264.

The furnaces 250 and 252 are separately fired by burners such as those indicated at 264 and 266, these burners being arranged and constructed similar to those previously described. The burners are arranged at one side of the

installation opposite the flue 268 so that the gases from the furnaces must pass through opposite and substantially semi-circumferential gas passes. In the left gas pass the gases pass through the bank of superheater tubes 270 similar in construction to that previously described, this bank of tubes being disposed between the intermediate gas pass wall 272 and the adjacent part of the casing wall. The wall 272 is formed by steam generating tubes with interposed stud and refractory construction arranged in the same manner as the components of wall 254.

The superheater 270 is protected by a radially arranged bank of screen tubes 274 disposed between the burner 264 and the superheater. These tubes are relatively large diameter tubes arranged with wide spaces between them and connected at the upper and lower ends to the upper and lower drums. This bank of screen tubes also protects the bank of steam generating tubes 276 disposed between the wall 272 and the downcomer. Thus, high temperature gases in the furnace 250 pass over the tubes of the screen 274 and are divided by wall 272, some of these gases contacting the tubes of the superheater 270 and others passing over the steam generating tubes 276. Beyond these positions, the gases unite in passing over a part of a bank of radially arranged steam generating tubes 278 connected to the upper and lower drums and arranged between the wall 272 and the bank of screen tubes 280 in the manner clearly indicated in the drawings.

The gases from the furnace 250, passing partially through the bank of steam generating tubes 278, unite with other furnace gases from the furnace 252 and pass from the installation through the flue 268, in which gas flow is controlled by the damper 282. The gases proceeding from the furnace 252 first pass over the tube screen 280 and then through part of the bank of steam generating tubes 278 to juncture with the gases from the furnace 250.

In the modification shown in Fig. 7, there is a single furnace 300, the gas flow from which is divided by the semi-circumferential wall 302. All of the gases first pass over the bank of screen tubes 304 and they are then separated between the superheater gas pass 306 and the steam generating gas pass 308. The gas flow through the gas pass 308 is controlled by the regulation of the damper 310 disposed in the flue 312. The latter is arranged adjacent a radial wall 314 which combines with the wall 302 and the radial wall 316 to complete the steam generating gas pass. The wall 314 is strengthened at an intermediate position by the stiffener 323, because of the wide difference in pressures on opposite sides of the wall. The steam generating tubes disposed within gas pass 308 are arranged in a semi-circumferential bank extending from the screen 304 around the downcomer 320 and to a position 322 adjacent the flue 312.

Within the gas pass 306 is arranged a superheater 324 constructed in a manner similar to that of the previously described superheater, and consisting of a bank of upright tubes. Beyond the superheater steam generating tubes are arranged in radial rows and disposed as a bank of tubes 327 extending from a position adjacent the screen tubes 326 to a position adjacent the flue 328. The gas flow through the superheater gas pass 306 and total steam temperature are controlled by the regulation of the damper 330 disposed across the flue 328.

The furnace of the Fig. 7 modification is fired by burners such as 332 and 334.

The modification shown in Fig. 8 of the drawings involves a single furnace 350 fired by burners 352 and 354. The gases from this furnace are divided so as to flow semi-circumferentially to the flues 356 and 358 which are arranged at the side of the installation opposite the burners. The gas flow to the flues is divided at a position adjacent the flues by a radial wall 360 consisting of steam generating tubes and intervening stud and refractory constructions such as those previously described.

The furnace gases moving from the furnace 350 clockwise around the downcomer 362 first pass over the bank of large diameter screen tubes 364. They are then divided by the wall 366 so that part of the gases pass over the tubes of the superheater 368 on one side of this wall. The remainder of these gases, on the other side of this wall pass over a bank of steam generating tubes 370 arranged in radial rows between the downcomer 362 and the wall 366. Beyond this wall these two divisions of the gases reunite to pass over the bank of steam generating tubes 372 to the flue 356. The gas flow over the superheater 368, and hence the final steam temperature is controlled by the regulation of the damper 374 disposed in flue 356, as modified by the gas flow in counter-clockwise direction about the downcomer 362 from the furnace 350 to the flue 358. The latter gas flow is regulated by the damper 376.

The gases passing from the furnace 350 in counter-clockwise direction about the downcomer 362 first pass over and between the tubes of the bank of screen tubes 380. Beyond this screen the gases contact the tubes of a bank of steam generating tubes 382 arranged in radial rows and substantially filling the annular space between the screen 380 and the radial wall 360. The latter is provided with radially extending reinforcing members 361 and 363.

In the modification shown in Fig. 9 of the drawings, there is a single furnace 400 disposed on one side of a radially positioned wall 402. Immediately on the other side of this wall is a single flue 404 so disposed that the gases must pass in a counter-clockwise direction almost entirely around the entire installation.

The furnace 400 is fired by burners such as 406 and 408 preferably disposed at an intermediate elevation opposite the downcomer 410, as in the other modifications.

The gases first contact the large diameter tubes of the bank of screen tubes 412 disposed in radial rows as clearly indicated in the drawings. Beyond this bank of screen tubes the gases are separated by a wall 414 between a superheater gas pass 416 and a steam generating gas pass in which there is disposed a bank of steam generating tubes 418. Opposite this bank of steam generating tubes is a superheater 420, similar to the above described superheater.

At the outlet of the superheater gas pass 416 the gas passes over and between the large diameter screen tubes 422 and then over the major bank of steam generating tubes 424 disposed in radial rows and extending from the screen 422 to the flue 404 as clearly shown in the drawings. Gas flow through the flue 404 is controlled by the damper 426.

The exterior casing, and shell 180 of each of the modifications is provided with a casing access opening 68 to the superheater space, this

casing opening being disposed directly above the superheater and normally closed by an appropriate cover which may be normally welded in pressure tight condition, or secured in such condition by other appropriate means. When this cover is removed, access to the annular space between the casing and the central pressure vessel construction is provided. In this manner, the amount of tube cutting necessary in the original construction and in the maintenance is minimized because a large portion of the bent tubes of both the superheater and the steam generating surfaces may be passed through this opening.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

25. What is claimed is:

1. In a steam generator, a cylindrical metallic casing including a pressure tight cylindrical metallic shell having upper and lower heads formed with circular openings, a cylindrical steam and water drum extending through the opening in the upper head of the casing and secured thereto in pressure tight condition, a lower cylindrical drum extending through the opening in the lower head of the casing and secured thereto in pressure tight condition, a large diameter downcomer co-axial with the casing and the drums and directly connecting the latter, the annulus between the casing and the drum and downcomer assembly providing space for a furnace and space for heat absorbing surfaces, steam generating tubes forming part of said surfaces, said tubes being directly connected to the upper and lower drums, spaced tubes forming a superheater disposed within said annulus, means connecting the steam space of the upper drum to the superheater, and means including a circumferentially directed wall construction within said annulus and forming a circumferentially extending superheater gas pass adjacent the casing wall and having a radial width of less than that of the annulus, said gas pass leading from the furnace.

2. In a vapor generator, a cylindrical metallic pressure confining casing, a unitary assembly of upper and lower drums and a connecting downcomer disposed centrally of the casing with an annular space between the casing and the assembly, a furnace in said annular space, means firing the furnace, vapor generating tube directly connecting the drums and disposed within said annular space, a bank of spaced tubes forming a superheater disposed in said annular space, means including a wall construction dividing a part of said annular space into two radially positioned and circumferentially extending gas passes, the bank of superheater tubes being disposed in one of said gas passes and at least some of the vapor generating tubes in the other gas pass, and flue means extending through the casing so as to provide for the discharge of furnace gases from said passes.

3. In a vapor generator, a cylindrical metallic pressure confining casing, a unitary assembly of upper and lower drums and a connecting downcomer disposed centrally of the casing with an annular space between the casing and the as-

sembly, a furnace means in said annular space, fuel burner means, vapor generating tubes directly connecting the drums and disposed within said annular space, a bank of spaced tubes forming a superheater disposed in said annular space, means including a wall construction dividing the part of said annular space into circumferentially extending superheater and vapor generating gas passes, the bank of superheater tubes being disposed in one of said gas passes and at least some of the steam generating tubes in the other gas pass, and flue means extending through the casing so as to provide for the discharge of furnace gases from said passes.

4. In a steam generator, a casing with upper and lower heads formed with circular openings, the casing also including a cylindrical metallic shell connecting the heads, a cylindrical steam and water drum extending through the opening in the upper head of the casing and welded thereto in pressure tight condition, a lower cylindrical drum extending through the opening in the lower head of the casing and welded thereto in pressure tight condition, a large diameter downcomer co-axial with the casing and the drums and directly connecting the latter, the annular space between the casing and the drum and downcomer assembly providing space for a furnace and space for heat absorbing surfaces, a fuel burner for firing the furnace steam generating tubes forming part of said surfaces within said annular space, said tubes being directly connected to the upper and lower drums, spaced tubes forming a superheater disposed within said annulus, means for connecting the steam space of the upper drum to the superheater, an upright wall extending outwardly from the downcomer to the casing, means forming a furnace gas outlet through the casing at the side of said wall, and furnace gas supplying means communicating with said space at a position adjacent the opposite side of said wall.

5. In a vapor generator an upright tubular pressure vessel providing upper and lower fluid chambers integrally joined by a large diameter upright downcomer, horizontally spaced upright vapor generating tubes directly connecting said chambers and disposed circumferentially of the pressure vessel, a casing circumferentially enclosing said tubes so as to provide an annular space between the downcomer and the casing, an upright wall extending from the downcomer to the casing, means forming a furnace gas outlet through the casing adjacent one side of the wall, a first combustion chamber from which furnace gases pass over some of said tubes to said outlet, said combustion chamber being disposed adjacent one side of said wall, a superheater including tubes disposed across gas flow from said combustion chamber toward said outlet, and a second combustion chamber disposed within said annular space and beyond the superheater relative to gas flow, gas from the second combustion chamber passing over others of said tubes to said outlet without passing over the superheater tubes.

6. In a vapor generator an upright tubular pressure vessel including upper and lower liquid chambers directly connected by a large diameter downcomer, horizontally spaced upright vapor generating tubes including tubes directly connecting said chambers and disposed circumferentially of the pressure vessel, a gas tight casing circumferentially enclosing said tubes and joined to said chambers in pressure tight relationship,

an upright wall extending from one side of the downcomer outwardly to the casing, means forming furnace gas outlets through said casing at positions on opposite sides of said wall, a combustion chamber from which furnace gases pass through the separate gas passes over said tubes and to said outlets, a superheater including tubes disposed in one of said passes, at least some of said vapor generating tubes being disposed in the other gas pass, and means in at least one of the outlets for varying gas flow over the superheater to control superheat.

7. In a vapor generator, an upright tubular pressure vessel including upper and lower fluid chambers directly connected by an upright downcomer, horizontally spaced upright vapor generating tubes directly connecting said chambers and disposed circumferentially of the pressure vessel, a casing circumferentially enclosing said tubes and bounding a wide annular furnace gas space around the downcomer, an upright wall extending from the downcomer to the casing, means forming a furnace gas outlet on one side of said wall, a first combustion chamber from which furnace gases pass over some of said tubes to said outlet, said combustion chamber being remote from said wall, a superheater including upright tubes disposed circumferentially between said combustion chamber and said wall and in a gas pass radially outwardly spaced from the downcomer, and a second combustion chamber disposed between the superheater and said wall and at the side of the wall opposite the furnace gas outlet, some of said vapor generating tubes being disposed within said annular space and in a gas pass separated from the gas pass in which the superheater tubes are disposed.

8. In a vapor generator, an upright tubular pressure vessel including upper and lower fluid chambers joined by a downcomer, horizontally spaced upright vapor generating tubes directly connecting said chambers and disposed circumferentially of the pressure vessel, a casing circumferentially enclosing said tubes and forming the outer boundary of an annular furnace gas space around the pressure vessel, an upright wall extending across said space from the pressure vessel to the casing, means forming a furnace gas outlet on one side of said wall, a first combustion chamber from which furnace gases pass over some of said tubes to said outlet, an upright segmental wall intermediate the downcomer and the casing and forming a superheater gas pass along a part of the casing, a superheater including tubes disposed within said gas pass and circumferentially between said combustion chamber and said first mentioned wall, some of said vapor generating tubes being disposed in the gas pass between said segmental wall and the downcomer, and a second combustion chamber disposed between the superheater and said first wall.

9. In a vapor generator an upright tubular pressure vessel providing upper and lower fluid chambers directly joined by a large diameter downcomer, horizontally spaced upright vapor generating tubes directly connecting said chambers and disposed circumferentially of the pressure vessel, a casing circumferentially enclosing said tubes, an upright wall extending from the pressure vessel downcomer to the casing, means forming a plurality of furnace gas outlets on one side of said wall, a combustion chamber from which furnace gases pass circumferentially of the pressure vessel and over some of said tubes to one of said outlets, the combustion chamber being disposed at the side of said wall opposite

said outlets, a superheater including tubes disposed in the path of the gases passing from said combustion chamber to the other of said outlets, fuel burning means operatively associated with the combustion chamber, a second wall construction combining with the pressure vessel and the casing to provide two separate gas passes leading from a position adjacent the superheater to a position between said gas outlets, and means associated with one of said outlets to vary the gas flow therethrough to control superheat, some of the steam generating tubes being disposed on one of said gas passes and the superheater tubes in the other gas pass.

10. In a vapor generating installation, upper and lower fluid chambers integrally connected by a large diameter central downcomer, a metallic shell of larger diameter than said chambers, said shell being secured in a gas tight relationship to the upper and lower chambers and providing an annular space between the shell and the downcomer, a fuel burner operating through the shell and horizontally firing a furnace disposed in a sector of said annular space, horizontally spaced upright fluid heating tubes disposed within a convection sector of said annular space adjacent the furnace and communicating with at least one of said chambers, and means forming a furnace gas outlet through the shell, the furnace gas outlet being arranged beyond said horizontally spaced upright tubes and so disposed with reference to the fuel burner that gases flow arcuately from the furnace sector to and through the convection sector and transversely of said tubes.

11. In a vapor generating installation, a pressure vessel structure presenting upper and lower fluid chambers integrally connected by a large

diameter central downcomer, a cylindrical metallic shell of larger diameter than said chambers, said shell being secured in a gas tight relationship to the upper and lower chambers and providing an annular space between the shell and the downcomer, a fuel burner operating through the shell and horizontally firing a furnace disposed in a sector of said annular space, horizontally spaced upright fluid heating tubes disposed within a convection sector of said annular space adjacent the furnace and communicating with at least one of said chambers, and means forming a furnace gas outlet through the side of the shell, the furnace gas outlet being arranged beyond said horizontally spaced upright tubes and so disposed with reference to the fuel burner that gases flow arcuately from the furnace sector to and through the convection sector transversely of said tubes.

GEORGE W. KESSLER.
